UNITED STATES PATENT OFFICE.

ERNEST N. HUMPHREY, OF NEW BRITAIN, CONNECTICUT, ASSIGNOR TO THE TRAUT & HINE MANUFACTURING COMPANY, OF NEW BRITAIN, CONNECTICUT, A CORPORATION OF CONNECTICUT.

CUTTING DEVICE.

1,073,581.

Specification of Letters Patent. Patented Sept. 16, 1913.

Application filed March 1, 1913. Serial No. 751,395.

To all whom it may concern:

Be it known that I, ERNEST N. HUMPHREY, a citizen of the United States, residing at New Britain, Hartford county, State of Connecticut, have invented certain new and useful Improvements in Cutting Devices, of which the following is a full, clear, and exact description.

This invention relates to cutting devices, 10 and more particularly to a folding cutter of the type embodying a blade holder section and a guard section pivotally connected thereto and designed to receive and protect the cutting edge of the blade which projects 15 from its section.

The present invention aims to provide a simple folding device of this character, of compact structure and especially designed to protect the blade portion of the device 20 from injury. These and other advantages are fully described in the following specification, taken in connection with the accompanying drawings forming part thereof and illustrating a preferable embodiment of 25 the invention.

In these drawings: Figure 1 is a view in front elevation of the cutting device with the parts folded together. Fig. 2 is a view in front elevation of the parts extended, 30 with the cutting blade exposed ready for use. Fig. 3 is a view in end elevation of the parts shown in Fig. 1. Fig. 4 is a fragmentary view in elevation of the folded device illustrating the locking means employed. Fig. 5 is a fragmentary longitudinal sectional view taken through the device 35 when folded.

Referring to the drawings by numerals, 1 indicates a blade guard in the form of a 40 metal clip, this clip being of U-shape or channel cross section, and being formed preferably of sheet metal bent upon itself. One end of this clip is preferably rounded and has the bottom of its channel cut away 45 as at 2 to permit the attachment of the other portion of the cutting device. This portion comprises a blade holder formed of a metal clip 3 of channel or U-shaped cross section and having an end 4 offset at substantially 50 right angles thereto and inserted within the recessed end of the channel clip 1. This holder clip 3 receives one edge of a cutting blade 5, preferably of the wafer type, which blade extends substantially the entire length 55 of the clip, preferably to a point closely ad-

jaacent the offset end thereof. The blade-receiving portion of the clip 3 terminates relative to its offset end 4 so as to bring the adjacent side edge of the blade 5 within the recessed channel end 2 of the guard clip 1 60 at all times. The overlapping ends of the two clips are pivotally connected together by means of a rivet stud 6 having its end upset against a washer 7 located on the side of the clip opposite the rivet head. The 65 recessed end of the guard clip 1 overlaps and incloses the adjacent side edge of the blade 5 at all times and maintains said blade in the plane of the channel of said guard section at all times, guiding it therein 70 when the parts are moved from extended into folded position and retaining its edge within said channeled portion when the parts are extended, this being possible because said blade edge is positioned adjacent 75 the point of pivotal connection of said overlapping ends. By providing one of these sections with an end offset at approximately a right angle thereto and pivotally connected to the recessed end of the other section, 80 the two sections may be folded to bring their edges closely adjacent and parallel to each other and in the same plane so that a very compact structure is afforded. Furthermore, it will be noted that when the 85 blade section is fully opened, the rear edge of its offset 4 will rest against the edge of the guard section adjacent the recessed end 2, and that this will take the load strain off 90 the pivot stud and locking projection hereinafter described.

In order to provide means for detachably locking the parts in extended position or when the blade-holding section is unfolded for use and for detachably locking said parts in folded position, I have provided sockets 8 in the recessed pivoted end of the guard section 1, these sockets being located at diametrically opposite points radially of the pivot 6. Coöoperating with the sockets are projections 9 carried by the offset end 4 of the blade holder section and positioned to snap into one or the other of the sockets 8 when the blade holder section is moved from folded to unfolded position. This affords a 105 frictional lock, sufficient under ordinary circumstances to hold the parts in opened or closed position, there being sufficient clearance between the inclosed sides of the channel clip 1 and the offset end 4 to permit the 110

projections 9 to spring out of the locking sockets 8 when the parts are swung from one position to another.

The blade holder and guard sections are preferably made of stamped sheet metal, the locking recesses and projections being readily stamped therein. The cutting blade 5 is preferably of the thin safety razor type, making the device very thin and compact 10 when folded.

While I have herein described a specific embodiment of the invention, it should be understood that the same may be altered in detail and relative arrangement of parts 15 within the spirit of the invention and the scope of the appended claims.

What I claim, therefore, and desire to secure by Letters Patent is:

1. In a device of the character described, 20 in combination, a clip of channel cross section having one end offset and extending at substantially a right angle, a second clip of channel cross section having one end overlapping the offset end of said first clip, one 25 of said clip ends being recessed to receive the overlapping end of the other, means for pivotally connecting the overlapping ends of said clips and a blade seated within one of said clips with one edge extending to a 30 point adjacent the point of pivotal interconnection of said ends whereby said edge is maintained at all times within and is guided by the overlapping end of the other clip.

2. In a device of the character described, 35 in combination, a clip of channel cross section having one end offset and extending at substantially a right angle, a second clip of channel cross section having one end overlapping the offset end of said first clip, one 40 of said clip ends being recessed to receive the overlapping end of the other, means for pivotally connecting the overlapping ends of said clips and a blade seated within one of said clips with one edge extending to a 45 point adjacent the point of pivotal interconnection of said ends whereby said edge is

maintained at all times within and is guided by the overlapping end of the other clip, the edge of the recessed clip adjacent its recessed end providing a bearing abutment for the 50 adjacent edge of the other clip when the parts are moved to fully opened position.

3. In a device of the character described, in combination, a blade-holding clip of channel cross section having one end offset and 55 extending at substantially a right angle, a second and guard clip of channel cross section having one end recessed to receive and overlap the offset end of said first section, means for pivotally connecting said overlapping ends, and a blade seated in said first clip with its cutting edge projecting therefrom to seat in said guard clip, said blade being positioned in said first clip to bring one edge adjacent the point of pivotal connection of said ends whereby said blade edge is maintained at all times within and guided 60 by the overlapping end of said guard section. 65

4. In a device of the character described, 70 in combination, a blade-holding clip of channel cross section having one end offset and extending at substantially a right angle, a second and guard clip of channel cross section having one end recessed to receive and 75 overlap the offset end of said first section, means for pivotally connecting said overlapping ends, and a blade seated in said first clip with its cutting edge projecting therefrom to seat in said guard clip, said blade being positioned in said first clip to bring 80 one edge adjacent the point of pivotal connection of said ends whereby said blade edge is maintained at all times within and guided by the overlapping end of said guard section, and co-operating locking means on said overlapping ends for locking said clips in folded and opened positions. 85

ERNEST N. HUMPHREY.
